UNITED STATES PATENT OFFICE.

GEORGE W. MAXWELL, OF CHICAGO, ILLINOIS.

EMBROIDERING DEVICE.

1,354,119.

Specification of Letters Patent. Patented Sept. 28, 1920.

Application filed October 20, 1919. Serial No. 331,885.

To all whom it may concern:

Be it known that I, GEORGE W. MAXWELL, a citizen of the United States, residing in the county of Cook, city of Chicago, and 5 State of Illinois, have invented new and useful Improvements in Embroidering Devices, of which the following is a specification.

This invention relates to an embroidering device particularly useful in practising a method of embroidering in which the needle carrying the thread is not passed bodily through the cloth being embroidered, but in which the needle point carrying the 10 thread is projected successively through the cloth and withdrawn, so as to form a succession of loops on the face of the cloth.

The needle by means of which such embroidery is carried on is usually of tubular 20 form, the thread being passed down through the body of the needle and then through an eye near the point of the needle. The needle is usually held removably in a handle, or holder.

25 The general object of my invention is to provide a holder of simple construction which can operate as a handle to hold two needles of different diameters, at different times, and which can also operate when desired to hold two needles of equal diameter simultaneously along side of each other so that the embroidering can be done with two threads simultaneously; to this end, one of my objects has been to construct the 30 handle of the holder in such a way that it is reversible. In one position of the holder the openings which could carry needles, operate as guides for the thread passing through the needle held at the opposite end 35 of the holder. That is to say, one of my objects is to produce a very simple and compact holder, or handle, operating as a holder for the needle and as a thread guide, and which is capable of holding two needles or 40 the same diameter simultaneously, or two other needles of different diameters.

45 The invention consists in the novel features, and in the general combination of parts to be particularly described hereinafter, all 50 of which contribute to produce a simple and efficient embroidery device. A preferred embodiment of my invention will be particularly described in the following specification, while the broad scope of my invention 55 will be pointed out in the appended claims.

In the drawing,

Figure 1 is a side elevation of an embroidery needle holder and thread guide embodying my invention and illustrating the same when used to hold two needles adjacent to each other;

Fig. 2 is a view similar to Fig. 1, but showing the holder and thread guide in a reversed position and carrying a single needle of a relatively small diameter;

Fig. 3 is a perspective illustrating the holder and thread guide as used with an embroidery needle of a larger diameter than that shown in Fig. 2;

Fig. 4 is a plan of a blank from which one 70 of my needles may be readily formed;

Fig. 5 is a plan of a blank from which another form of needle may be readily produced;

Fig. 6 is a side elevation of the lower end 75 of one of the needles illustrating details of its construction; and

Fig. 7 is a diagrammatic view illustrating the manner of using such a needle in embroidery.

In practising my invention, I provide a handle, or holder, preferably in the form of a frame 1 which may present two oppositely disposed flat side bars 2 and transverse end bars 3 and 4. This frame is most conveniently formed by bending a strip of flat metal into the shape shown in Fig. 1, the end bar 3 being formed integrally with the side bars 2, and the other end bar 4 being formed by bending the ends of the bar into end sections 4^a and 4^b integral with the side bars 2, which end sections project toward each other, but which are preferably separated at their end faces by a narrow gap 5 so that the entire frame has a certain amount of resiliency, or spring effect.

The handle is provided with means for carrying the needles. In the present instance, the end bar 3 is provided with two openings 6 of equal diameter adapting it to hold simultaneously two embroidery needles 7 and 8. The bodies of these needles 7 and 8 are substantially similar, that is to say, the bodies are of tubular form, with quill shaped lower ends, each provided with an opening, or eye, through which the embroidery threads 9 and 10 pass. However, the upper portions of these needles are not identical in shape on account of the fact that the needle points are preferably disposed toward 105 the same side of the handle.

The needle 7 may be simply formed from

a blank 11 having the general characteristics of the blank shown in Fig. 4, that is to say, the blank consists of an elongated strip having a slot 12 at its upper end and tapering to a point 13 at its lower end. Near the middle portion of the blank, laterally disposed lugs 14 are formed, having small shoulders 15 near the lower edges thereof. The lower part of the blank has lugs 16, the outer edges 5 of which are in alinement with the shoulders 15. In forming the needle, the lower portion 10 of the blank is rolled on a longitudinal axis into a cylinder so that the adjacent edges of the lugs 16 abut against each other, and so that the shoulders 15 abut against each other, (see Fig. 6). The lugs 14 become superposed upon each other and are 15 bent outwardly so as to enable them to co-operate with means on the holder for securing 20 the needle in position. I do not limit myself to these details however, and any suitable means may be provided for enabling the needle and the holder to coöperate to hold the needle in position. When the needle 25 is constructed as the needle 7 is constructed, I simply provide the side bars 2 with small rectangular, or square, openings 17 which receive the lugs 14 when the body of the needle has been passed downwardly through 30 the opening 6, (see Fig. 1). In order to enable the amount of penetration of the needle to be regulated, I prefer to provide a row of the openings 17, extending longitudinally along the side bars.

35 The needle 8 may be conveniently formed from a blank having the characteristics of the blank 18 (see Fig. 5). This blank has the general shape of the blank 11 except that near its middle point it is provided with two 40 oppositely projecting lugs 19 disposed between shallow slots 20 and the upper end of the blank is provided with a longitudinal slot 21 which extends through the upper edge, or end of the blank and is not a closed slot such as the slot 12. This blank 18 is 45 bent into shape, substantially in the manner described in connection with the needle 7, and the lugs 19 are bent around so as to form dogs 22 which may project through openings 17 in the opposite side bar 2. When the needles are in position their upper ends extend upwardly along the side bars 2 of the holder and are bent laterally so as to form 50 overlapping tails 23, see Fig. 1; in forming these tails the slot 12 is made to aline with the slot 21. In the other end, or upper end 55 of the frame as viewed in Fig. 1, openings 24 and 25 are provided, respectively, in the end bar sections 4^a and 4^b. These openings 60 operate as thread guides for the threads 10 and 9, respectively, which pass downwardly through the alining slots 12 and 21, and thence through the tubular bodies of the needles 7 and 8.

These openings 24 and 25 are of different 65 diameters from each other and are also of different diameters from the openings 6 at the other end of the frame.

When it is desired to use the holder for a needle of small diameter I remove the 70 needles 7 and 8 and reverse the position of the holder; that is to say, I hold it with its small end down, and I mount in the opening 25, a small needle 26. This needle is formed from a blank the body of which is bent into 75 tubular form, the upper end of the blank being bent to form a lateral extension or tail which is made of tubular form by rolling the flat blank into a cylindrical shape. This end of the frame is provided with 80 means for coöperating with the needle to hold it in the handle. For example, I provide one of the side bars 2 with a row of openings 28 for this purpose. The thread 29 passes up through the tubular body of the 85 needle 26 and is guided through the opposite opening 6 in the other end of the handle.

The needle 26 is the smallest needle which can be mounted in the holder or handle. A needle 30 of intermediate size may be 90 mounted in the handle in the opening 24. This needle 30 is formed similarly to the needle 26, except that its upper end is offset as at 31 so as to permit the thread 32 to pass straight down into the upper end of the 95 tubular body of the needle. This offset is made necessary by reason of the fact that the eye 33 of this needle is on the same side as the eye of the needle 26.

The manner of using an embroidering device of this type is illustrated in Fig. 7; the needle is pushed successively partially through the cloth 34 and withdrawn so as to form a series of loops 35 on the underside of the cloth, which becomes the "right 105 side" after the embroidery is completed.

In using the embroidering device, the end of the handle operates as a stop to limit the penetration of the needle. The amount of projection of all of the needles may be regulated, because I provide a row of openings corresponding to each needle. In the case of the needle 30, I provide a row of openings 36 opposite to the openings 28 and co-operating with the needle 30 in the same 115 way as the openings 28 coöperate with the needle 26.

The handle 1 is preferably larger at one end than the other, and this effect may be attained by forming the frame so that the 120 side bars 2 converge slightly toward each other throughout their entire length. If this is done, it enables me to use a sliding sleeve 37 of rudimentary form, (see Fig. 2) which may be slid toward the large end 125 of the frame so as to spring the bars 2 nearer together at the small end of the frame; this gives a slight movement of the

bars 2 at the small end of the frame which may be utilized to assist in securing the needles 26 or 30 in the frame.

What I claim is:

- 5 1. An embroidering device comprising a reversible handle in combination with two detachable tubular embroidery needles, mounted in substantially parallel relation at one end of said handle, the opposite end 10 of said handle having openings of different size capable of receiving embroidery needles and adapted to operate as guides for the threads passing to the embroidery needles mounted at the opposite end of the handle.
- 15 2. A reversible handle for holding embroidery needles, having an opening at one end for a needle of one diameter and having an opening at the other end for a needle of another diameter, said handle further 20 having means adjacent each end thereof to coöperate with a needle to secure the same in the handle, the opening at one end of the handle operating as a guide for the thread passing to a needle held at the other 25 end of the handle.
3. A reversible handle for holding embroidery needles of different diameters, consisting of a frame comprising two substantially flat side bars and end bars, one 30 of said end bars having two openings of substantially equal diameter therethrough to receive embroidery needles of equal diameter, the other end bar having two openings of diameters different from each other

and different from the diameter of said 35 first named openings, each of said last named openings being adapted to hold a needle of a diameter corresponding thereto, said frame, adjacent each end thereof, having means to coöperate with the embroidery 40 needles to secure the same in the ends of the holder, an opening at either end of said holder operating as a thread guide for a needle mounted at the opposite end of the holder. 45

4. A reversible handle for holding embroidery needles of different diameters consisting of a frame formed of a flat bar bent so as to have two side bars connected at one end by an integral end bar, the opposite ends of said side bars having end bar sections projecting toward each other and forming an end bar for that end of the handle, said first named end bar having a pair of openings therethrough of equal 55 diameter for holding two embroidery needles of equal diameter, said end bar sections each having an opening therethrough, said last named openings being of unequal diameter to enable each of the same to hold an embroidery needle of a different diameter from that of the other, said side bars adjacent each end of the holder having means to coöperate with the embroidery needles to secure the same in the holder. 60 65

In testimony whereof, I have hereunto set my hand.

GEORGE W. MAXWELL.
